INVENTORS:

Morris Friedman, Meyer Friedman

BY

Geo. F. Neath

ATTORNEY

UNITED STATES PATENT OFFICE.

MORRIS FRIEDMAN AND MEYER FRIEDMAN, OF NEW YORK, N. Y.

LEGGING.

Application filed June 1, 1925. Serial No. 33,910.

To all whom it may concern:

Be it known that we, MORRIS FRIEDMAN, a citizen of Russia, having declared my intentions of becoming a citizen of the United States, and MEYER FRIEDMAN, a citizen of the United States, both residents of the borough of Bronx, county of Bronx, city and State of New York, have invented certain new and useful Improvements in Leggings, of which the following is a specification sufficient to enable those skilled in the art to which the invention appertains to utilize the same.

Our improvements relate to leggings generally, and particularly those made of leather or analogous material designed to be closed and fastened on their outer sides, the object of our invention being primarily to adapt such leggings to the combination and incorporation therewith of hookless fastenings, so-called, in such manner as to render the use of such fastenings practical and convenient by forming the lower extremities of the conjunctive edges of the legging with extension tips which facilitate the application to or removal from the foot and ankle of leggings so equipped with side fastenings of the hookless type, as hereinafter fully set forth,—the invention consisting in the specific combination, construction and arrangement of parts described and claimed, whereby these and other advantageous results are attained.

In the accompanying drawings we illustrate a practical embodiment of the essential features of our invention as embodied in a legging of the character designated, although we do not limit ourselves to the identical configuration of component parts of the legging shown by way of exemplification, since changes may be made in form and minor details with like results, and without departing from the spirit and intent of our invention in this respect.

With this understanding:—

Fig. 1, represents an outer side elevation of our improved legging, closed;

Fig. 2, a similar view of the parts shown in Fig. 1, as opened up.

The general configuration and construction of our leggings A, is essentially the same as heretofore, they being furnished in pairs of rights and lefts, and that shown

in the drawings by way of example being for the left leg of a wearer.

The conjunctive longitudinal edges a, a, of the legging A, are formed at their lower extremities with extension tips a^x, a^x, protuberant beyond the lower transverse circumscribing edge a', of said legging A, as will be seen by reference more particularly to Fig. 1, of the drawings, said extension tips a^x, a^x, being secured to one end of the instep strap i, which thus practically constitutes a unitary basic prolongation of said extension tips a^x, a^x, thereby reinforcing and strengthening the same.

The inner otherwise free end of the instep strap i, is formed with perforations for engagement with the tongue of a buckle b, attached to the inner side of the lower edge a', of the legging as shown in Fig. 2, of the drawings.

The provision of the extension tips a^x, a^x, enables us to prolong the conjunctive longitudinal edges a, a, so far below the transverse circumscribing edge a', of the legging that it is practicable to incorporate with said longitudinal edges a, a, the serrated strips s, s, of hookless fastenings of a type now well known in the art of detachably connecting opposed edges of various kinds and articles, the tips a^x, a^x, admitting of the extension of the lower ends of said hookless strips s, s, sufficiently below the said bottom edge a', of the legging to admit of the spreading apart thereof to facilitate application to the foot of the wearer, as will be understood by reference more particularly to Fig. 2, of the drawings, in which the copulative slide s', of said hookless fastening strips s, s, is shown as well down within the bifurcated opening between said extension tips a^x, a^x.

Obviously, if the united hookless fastening strips s, s, terminated at or above the lower edge a', of the legging A, the utility of the latter would be impaired because it could only be applied to relatively small feet owing to the contracted opening prescribed by the fixed lower edge of the legging.

It is to be understood that by the term leggings as herein employed we mean to include overgaiters and equivalent or analogous leg wear.

What we claim as our invention and desire to secure by Letters Patent, is:—

As an article of manufacture, a legging of the character designated, the conjunctive edges of which are formed at their lower extremities with extension tips, to which tips the lower ends hookless fastenings are at-

tached, together with said hookless fastening means arranged to detachably connect the said conjunctive edges of the legging, substantially in the manner and for the purpose set forth.

MORRIS FRIEDMAN,
MEYER FRIEDMAN.
